UNITED STATES PATENT OFFICE.

ARTHUR H. SCOTT, OF OAK LANE, PENNSYLVANIA.

PAPER TOWEL.

1,102,208.

Specification of Letters Patent. Patented June 30, 1914.

Application filed July 5, 1910. Serial No. 570,248.

To all whom it may concern:

Be it known that I, ARTHUR H. SCOTT, a citizen of the United States, and a resident of Oak Lane, county of Philadelphia, State 5 of Pennsylvania, have invented an Improvement in Paper Towels, of which the following is a specification.

My invention has reference to paper towels and consists of certain improvements 10 which are fully set forth in the following specification and shown in the accompanying drawings which form a part thereof.

The object of my invention is to provide a cheap form of toweling, formed from paper and adapted for all general use of the 15 lavatory, factories, hospitals, laboratories and general use with an embodiment of cleanliness and antiseptic qualities.

My object is also to form the toweling in 20 rolls, so that only one towel at a time can be exposed and detached; and moreover I prefer to provide the towel with an attached strip of soap-suds producing material which may be detached from the towel after it is 25 detached from the roll and used preliminary to the drying purposes of the towel.

In carrying out my invention, I form a web of paper into a roll, the said web of paper having transverse perforations at intervals, to enable the successive portions of 30 the web to be detached from the roll to provide independent towels, as may be required; and moreover, the said web of paper is made of a porous character having little sizing 35 and of a crinkled character, for the purpose of increasing the absorbent qualities within a given area, and also for softening the texture of the paper to impart to it more or less quality of a textile fabric, that is to say, one 40 capable of being thoroughly flexible in all directions. I, further, prefer to form the said web of paper with additional perforations to provide a strip adjacent to each towel portion, which strip is detachable from 45 the towel and is coated or impregnated with a soap substance and normally dry, but which may produce a lather when the strip is removed from the towel and employed in connection with water for performing the 50 functions of a cake of soap preliminary to the use of the towel for drying purposes.

My invention further comprehends a

towel of the above character when having its crinkled surfaces provided with a coating of talcum or other suitable powder. 55

My invention also comprehends details of construction which, together with the features above specified, will be better understood by reference to the drawings, in which:—

Figure 1 is an elevation of a roll of my improved toweling, partly unrolled, to expose a complete towel; Fig. 2 is a side elevation of the same; Fig. 3 is a cross section of a portion of the toweling to indicate the crinkled form of the paper and a coating of powder thereon; Fig. 4 is a front elevation of a roll of my improved toweling, showing a modified construction thereof; and Fig. 5 is an end view of a modified form 70 of my invention.

A, is the rolled web of the paper and this web is divided at intervals throughout its length by transverse incisions or weakened parts, indicated at C and producing between the successive incisions or perforations the individual towel portions B.

The paper from which this toweling is made is of a very porous character, having but little sizing and having a finished 80 crinkled condition of the body so as to produce greatly increased surface within a given area relatively to what would be had if the paper were perfectly smooth. This crinkled condition of the paper not only 85 gives a greater absorbent capacity to a towel of a given size because of the increased surface exposed, but also increases the absorbent qualities by reason of the fact that innumerable depressions or pockets are 90 formed by the crinkled structure of the paper which will retain and hold moisture by capillary action in addition to the said absorbent qualities.

The absorbent qualities of the crinkled 95 paper is still further enhanced by coating the surfaces of the paper with finely pulverized talcum powder or other equivalent which, while not adding greatly to the thickness, will be retained within the depressions or pockets and will provide soothing effect of the paper upon the face and hands in addition to capacity for absorbing the moisture. A paper of this character

would be most excellent as a towel for days of great humidity to remove the perspiration and oiliness from the skin.

The transverse perforations C are preferably made sufficient to weaken the connection of the successive towels so that a pull upon the liberated towel will detach it from the remaining web in the roll form and without inducing an objectionable unwinding of the roll, the object being to only induce the detachment of one towel at a time.

In many places of use of such towels the absence of a soap renders it important that provision shall be made for providing a 15 cleansing lather to facilitate the washing, preliminary to the use of the towel as a drying medium, and to provide such means I may form the web of paper near one edge thereof with a line of perforations E extending 20 throughout the length of the web and coat or impregnate the strip of paper between said line of perforations and the edge of the web with a soap material which may be applied, if desired, as a paste or in liquid 25 form to impregnate the paper and coat the surface thereof among the depressions or pockets formed by the crinkled structure of the paper, such strip of soap-suds producing material being indicated at D. In practice, 30 the towel portion B, with the attached strip D, is broken off from the web on the perforated line C and then the strip D is torn from the towel proper B and is used with water for the purpose of providing the soap-35 suds. The towel part B is thus isolated from the soap and may be used freely for drying the skin. If desired, the line of perforations E, instead of being lengthwise of the web, as shown in Fig. 1, may be arranged trans-40 versely thereof at intervals adjacent to the transverse lines of incisions C, as clearly indicated in Fig. 4 in which E' is the transverse line of perforations, and D' is the transverse strip of soap prepared paper. In 45 this construction, shown in Fig. 4, it is desirable that the incisions at C shall be weaker than the perforations at E' so that in detaching a sheet the strip of soap paper will be removed with the towel. This might be 50 improved somewhat if the web was wound in the reverse direction to what is shown in Fig. 4, in which case the soap paper strip would come at the bottom of the towel, but I do not restrict myself in this respect.

55 While ordinarily, a single ply towel may be amply sufficient to secure the desirable absorbent qualities, I provide in other cases an extra capacity for absorbing moisture by making the web in double layers or two-ply 60 and perforated as before, so that two sheets or plies, superimposed one upon the other, are removed at one time and used as a single towel. This is shown in Fig. 5, in which A is the roll, B is the two-ply towel, 65 and C are the perforations or weakened por-

tions. These perforations or incisions are preferably made at exactly the same place in both plies, as by cutting through them both at the same time with a single cutter. The two-ply towel has greater absorbent capacity than a single ply towel of the same weight and is moreover far more flexible and pleasant to use.

Having now described my invention what I claim as new and desire to secure by Letters Patent is:—

1. As an article of manufacture a roll of paper towels consisting of a long web of crinkled paper of great absorbent qualities transversely perforated at intervals in its length to form detachably connected towels and rolled upon itself, the said paper having its surface and recesses provided by the crinkled formation coated with an absorbent powder, and said web being further perforated to provide adjacent to and detachably annexed to each towel a strip containing a lather producing substance.

2. As an article of manufacture a roll of paper towels consisting of a long web of crinkled paper of great absorbent qualities transversely perforated at intervals in its length to form detachably connected towels and rolled upon itself, the said paper having its surface and recesses provided by the crinkled formation coated with an absorbent powder, and said web being further perforated throughout its length near one edge to provide adjacent to and detachably annexed to each towel a strip containing a lather producing substance.

3. As an article of manufacture a roll of paper towels consisting of a two-ply long web of crinkled paper of great absorbent qualities transversely perforated at intervals in its length to form detachably connected two-ply towels and rolled upon itself, the said paper having its surface and recesses provided by the crinkled formation coated with an absorbent powder, and said web being further perforated to provide adjacent to and detachably annexed to each towel a strip containing a lather producing substance.

4. As an article of manufacture a roll of paper towels consisting of a two-ply long web of crinkled paper of great absorbent qualities transversely perforated at intervals in its length to form detachably connected two-ply towels and rolled upon itself, the said paper having its surface and recesses provided by the crinkled formation coated with an absorbent powder.

5. As an article of manufacture, a roll of paper towels consisting of a long web of highly absorbent crinkled paper, perforated transversely at intervals in its length to form detachable towels and rolled upon itself, said web being further perforated to provide a detachable strip containing soap.

6. As an article of manufacture, a package of paper towels consisting of sheets of highly absorbent paper having its surface formed with recesses and containing an absorbent powder in the said recesses.

7. As an article of manufacture, a package of paper towels consisting of sheets of highly absorbent paper, a portion of the

surface of which contains a lather producing substance.

In testimony of which invention, I hereunto set my hand.

ARTHUR H. SCOTT.
